UNITED STATES PATENT OFFICE.

WALTER M. THOMPSON, OF GRANITE FALLS, MINNESOTA.

AUTOMATIC SCREEN.

1,008,499.

Specification of Letters Patent. Patente 1 Nov. 14, 1911.

Application filed December 12, 1910. Serial No. 596,826.

To all whom it may concern:

Be it known that I, WALTER M. THOMPSON, a citizen of the United States, residing at Granite Falls, in the county of Yellow Medicine and State of Minnesota, have invented certain new and useful Improvements in Automatic Screens, of which the following is a specification, reference being had to the accompanying drawings.

10 My invention relates to improvements in stage appliances more particularly to an improved draw screen or curtain.

The object of the invention is to provide a screen which is so mounted that it may be readily drawn out of the way to one side of the stage or platform and which when released will be automatically stretched across the stage or platform.

With the above and other objects in view 20 the invention consists of the novel features of construction and the combination and arrangement of devices hereinafter fully described and claimed and illustrated in the accompanying drawing, in which I have 25 shown a perspective view of my improved draw screen or curtain.

In the drawings 1 represents a proscenium arch of a stage or any other upright supports between which a screen curtain or the like 2 may be hung. This screen is flexible so that it may be drawn to one side and, as illustrated, it is of rectangular shape and has at its top metal guide eyes 3 to slide upon a suspending wire or cable 4. The 35 latter forms a supporting track or guide for the screen and has one end passed over a pulley in a double pulley block 5 hung from a hook 6 or otherwise suitably connected to the upper portion of the support 1. Said 40 end of the wire 4 extends downwardly and is connected by a stretching device 7 to the lower portion of the support 1 or to the floor. The device 7 may be of any suitable form and construction but, as illustrated, 45 it is in the form of a turn-buckle having one end connected to a stationary hook 8 and its other end provided with an eye which is engaged with a snap hook 9 on the end of the wire 4. The other end of the wire 4 50 passes over one of three pulleys in a pulley block 10 hung from a hook 11 on the other side of the support 1 and the last mentioned end of the wire 4 extends downwardly and is connected to a stretching device 12, similar to the device 7. By the means of these

stretching devices 7, 12 the supporting wire or track 4 for the curtain may be kept taut.

An operating and adjusting rope 13 is passed over one of the pulleys in the block 10 and has its upper end connected by a snap hook 15 to the adjacent upper or right hand corner of the screen 2 and its other end extends downwardly and may be engaged with a cleat 14 so that the rope 13 will limit the movement of the screen to the left. A second operating and adjusting rope 16 is arranged upon the other side of the device and passed around the other pulley in the block 5. The upper end of the rope 16 is connected by a snap hook 17 to the upper left hand corner of the screen 2 and said rope extends downwardly and has secured to it a weight 18 which is sufficient to draw the screen to its stretched position. Said weight 18 is preferably hooked into a metal guide member 19 arranged at the lower end of the rope 16 and adapted to slide upon the vertical portion of the wire 4 which latter thereby serves as a guide for the weight. A cord 20 may be attached 80 to the weight so that the latter may be pulled down should the screen become caught. A third operating cord 21 is provided and has its upper end passed over the third pulley in the block 10, then through the rings 3 at the top of the curtain and connected by a snap hook 22 to the upper left hand corner of the curtain. The other end of the rope 21 extends downwardly and may be engaged with the cleat 14 or with a similar one, or it may be fastened in any other manner.

23 denotes a weight attached to the center of the bottom edge of the screen to hold the latter steady and 24 denotes two coil springs 95 suitably fixed at one end and having the other end detachably engaged with the lower corners of the screen.

In operation assuming the screen to be in its stretched position shown in the drawings, when it is desired to draw the screen to one side of the stage and out of the way, the springs 24 are disconnected from it and the lower end of the rope 21 is drawn upon so that the rings 3 at the top of the screen will be moved to the right and toward each other to fold the screen and position it in a folded position at the right hand side of the stage. As the screen is thus drawn or folded the weight 18 is elevated so that the 110

instant the rope 21 is released the weight 18 will descend and automatically stretch the screen to its position shown in the drawing. By fastening the end of the rope 21 5 to the cleat 14 after the screen has been drawn over or folded the latter will be retained in such position, and by adjusting the cope 13 the screen may be positioned centrally between the supports 1.

10 While I have shown and described in detail the preferred embodiment of my invention, I wish it understood that I do not limit myself to the precise construction set forth, and that various changes in the form 15 and construction and minor details may be resorted to without departing from the spirit or sacrificing any of the advantages of the invention.

Having thus described my invention what 20 I claim is:

An automatic screen comprising in combination a drawn screen, a plurality of rings disposed on the upper edge of said screen, a wire track for said rings, a wire rope for 25 drawing said screen up, a hook disposed on

said last mentioned rope, a rope secured to one of said rings disposed at the corner of said screen, a catch disposed on said rope, a turn-buckle disposed in said rope, a cleat for fastening said rope, another rope having a 30 catch thereon secured in one of said rings disposed in the opposite corner of said screen, a weight disposed on the end of said rope, a ring secured to said weight and arranged to engage with one of said ropes 35 for guiding said weight, pulleys disposed at the upper corners of said screen and arranged to guide the ropes, means for holding said pulleys, springs disposed at the lower corners of said screen, hooks for engaging with the other ends of said springs, and a weight disposed in the middle of the lower edge of said screen.

In testimony whereof I hereunto affix my signature in the presence of two witnesses. 40 45

WALTER M. THOMPSON.
